(57) **CLAIM**

The ornamental design for a vehicle hood vent, as shown and described.

DESCRIPTION

FIG. 1 is a top-front perspective view of a first embodiment of my new vehicle hood vent;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 depicts the vehicle hood vent of FIG. 1 mounted in a vehicle hood;

FIG. 8 is a top-front perspective view of a second embodiment of my new vehicle hood vent;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 depicts the vehicle hood vent of FIG. 8 mounted in a vehicle hood.

In the drawing figures, features shown in broken lines indicate environmental subject matter only, and form no part of the claimed design.
